DESIGN FOR A SHOETREE

James B. Mutch, Rochester, N. Y., assignor to SHELTER LAST CO. INC., Rochester, N. Y., a corporation of New York

Application October 27, 1942, Serial No. 108,619

Term of patent 14 years

To all whom it may concern:

Be it known that I, James B. Mutch, a citizen of the United States, residing at Rochester, in the county of Monroe and State of New York, have invented a new, original, and ornamental Design for a Shoetree, of which the following is a specificcation, reference being had to the accompanying drawing, forming a part thereof, and in which:

Figure 1 is a perspective view of a shoetree
showing my new design.

I claim:

The ornamental design for a shoetree, as shown.

JAMES B. MUTCH.
